UNITED STATES PATENT OFFICE.

HENRY OAKES, OF SILVER CITY, TERRITORY OF NEW MEXICO, AND BEN OAKES, OF CHICAGO, ILLINOIS.

CAR-COUPING.

SPECIFICATION forming part of Letters Patent No. 484,900, dated October 25, 1892.

Application filed October 27, 1891. Serial No. 409,993. (No model.)

To all whom it may concern:

Be it known that we, HENRY OAKES, residing at Silver City, in the county of Grant and Territory of New Mexico, and BEN OAKES, residing at Chicago, in the county Cook and State of Illinois, citizens of the United States, have invented a new and useful Car-Coupling, of which the following is a specification.

This invention relates to car-couplings, and more especially to the classes thereof known as "twin-jaw" and "rotary-head," and the object of the same is to effect certain improvements in devices of this character.

To this end the invention consists in a car-coupling embodying a construction substantially as hereinafter more fully described and claimed, and as illustrated on the two sheets of drawings, wherein—

Figure 1 is a perspective view of the end of a car with our improved coupling attached, showing the jaw in its normal position and viewing the whole slightly from the under side. Fig. 2 is a plan view of the draw-bar, draw-head, and jaw. Fig. 3 is a front elevation of the draw-head with the jaw removed. Fig. 4 is a bottom plan view of Fig. 2, showing the dog in dotted lines as engaging the jaw to hold the latter in uncoupled position, and omitting the ear. Fig. 5 is a bottom plan view of two draw-heads in the act of coupling. Fig. 6 is a central horizontal section through two draw-heads coupled.

Referring to the said drawings, 1 is the car-body, beneath which is the block 2. 3 is the draw-bar passing through this block and having an open mouth 4 with a rounded front end 5 and a vertical pin-opening 6. 7 is a vertical bolt passing through this draw-bar in rear of its mouth 4, and 8 is a plate on top of the draw-bar under the nut of this bolt, said plate moving in a slot 9 in the block 2, whereby the draw-bar has a slight vertical movement in addition to the longitudinal motion which is permitted by its buffer-springs, (not shown,) as well understood. The opening of the block 2 is extended laterally at its upper end to receive lateral projections of the plate, which projections extend beyond the sides of the draw-bar.

The draw-head has on its exterior an annular groove 10, around which turns the ring-

shaped body 11 of the jaw. Such jaw is double—that is to say, arms 12 project forward and outward from diametrically opposite sides of the ring, and carry at their front ends the jaws proper 13, which are oppositely beveled on their front faces, as shown at 14. When the jaws of two couplings of this character come together, the four faces 14 strike and slide over each other and the rings 11 (one or both) turn in the grooves 10, so as to permit the jaws to rotate relatively to a sufficient degree to permit their beveled faces to pass each other, as seen in Fig. 5. The lower jaw 13 of each coupling is weighted, as at 15, so that after the jaws pass each other the weights turn them to their normally-vertical position, and the rear faces 16 of the heads are in contact. Said faces are slightly dished, as at 17, Fig. 2, which prevents the jaws disengaging easily when under tension, and at this time the rounded ends 5 of the draw-heads permit the two couplings to have a slight lateral swinging movement, as will be obvious from an inspection of Fig. 6. This figure also shows how an ordinary link can be coupled into the mouth 4 of the draw-head when this coupling is connected with one of the conventional pin-and-link type.

For the purpose of uncoupling the cars, we provide the following devices: 20 is a bracket depending from the car-body and having a slot 21, and 22 is a rod passing through this slot, having a handle 23 at its outer end and having a block with notched ends 24 (or a pair of stops) on its underside. The inner end of this rod passes through a slot 25 in an ear 26, which is bolted or riveted to the lower jaw 14, the end of the rod having a T-head or cross-bar 27 for preventing its pulling through said slot, and at the other side of the ear an expansive spring 28 is coiled on the rod between a stop 29 thereon and the back of the ear. Thus when it is desired to uncouple the cars the handle 23 is grasped, the rod 22 is raised so as to disengage the outer end of the block 24 from the slot 21, and the handle is drawn out, whereby the head 27 of the rod will draw on the ear and turn the ring 11 around the draw-head. If it is desired to keep the coupling in uncoupled position, the rod is then lowered, so that the inner end of

the block 24 engages outside of the bracket 20. In the first position, if the draw-head were to be automatically coupled with another the spring would permit it to rotate 5 without necessarily moving the rod, as will be clear.

30 is a plate of inverted-U shape, which is secured to the lower side of the draw-bar 3 by the head of the bolt 7 and stands behind 10 the lower arm 12 of the jaw, and this plate has at one side a tongue 31, which projects forward and serves as a stop to prevent the weight 15 from turning the jaw beyond its proper vertical position.

15 32 is a rod passing through an eye in the bracket 20 and having a handle 33 at its outer end, the inner end of this rod being journaled through the downturned portions of said plate 30 and prevented from displacement by any means, as a split pin 37. On the 20 rod within the plate is keyed or otherwise secured a dog 39, whose tip is adapted to be turned forward and upward into a notch 35 in the lower arm 12. With this construction 25 the rod may be turned so as to cause the tip of the dog to stand in the notch 35 when the jaw is in vertical position, thus locking it against an automatic uncoupling, and the friction of the rod in the eye of the bracket 30 will prevent the dog falling; or, after the jaw has been swung to uncouple, the dog may be turned forward behind a lug 35' on the body 11 to hold it in this position, as seen in dotted lines in Fig. 4. These devices are 35 preferably auxiliary to those above described for operating the device. Still either set of devices could be used for this purpose.

A car-coupling of this character possesses great strength and durability, is automatic in 40 its action, is positive when locked, and is yet easy to uncouple or to lock in uncoupled position. If the cars do not stand exactly in the same horizontal plane, the couplings will work nearly if not quite as well, and should 45 one draw-bar become detached from its support it cannot fall to the ground, and thus perhaps derail a car, because the upper jaw would strike on the front end of the draw-head before the two jaws above said head became disconnected. When two cars come together and the jaws are deflected from a 50 vertical line, the faces of the draw-heads strike each other and act as buffers, thereby taking all the strain off the jaws at this time and 55 allowing the weights 15 to cause the jaws to turn to a vertical position and interlock.

We do not confine ourselves to the exact details of construction, as considerable change 60 may be made therein without departing from the spirit of our invention. Neither do we limit ourselves to the use in a single device of all the elements and features above described, as some of them might be used alone or in other connections to great advantage. 65 The sizes, shapes, and materials of parts are matters of no moment with respect to the

novelty of the invention, and are hence not elaborated herein.

What is claimed as new is—

1. In a car-coupling, the combination, with 70 a draw-bar having at its front end a draw-head whose front face is slightly curved transversely, said draw-head being provided with a mouth intersected by a pin-opening and exteriorly with a groove, of a ring turning in 75 said groove, arms projecting forward and outward from said ring, and jaws at the outer ends of said arms, having oppositely-beveled faces.

2. In a car-coupling, the combination, with 80 the car-body, a block on the end thereof, having a slot extended laterally at the upper end, and a draw-bar extending through said slot and having a draw-head, of a vertical bolt through said bar and a plate secured 85 upon the bar by the bolt and projecting laterally from the draw-bar and moving in the extensions of the slot.

3. In a car-coupling, the combination, with 90 a draw-bar having a draw-head and a plate secured beneath said bar and having a forwardly-projecting tongue, of a rotary jaw mounted on said head and resting normally against said tongue.

4. In a car-coupling, the combination, with 95 a draw-bar and a plate secured beneath the same and having a forwardly-projecting tongue, of a rotary jaw connected with said bar and resting normally against said tongue, this jaw having a beveled face at its front 100 end, and means for drawing the jaw away from said tongue.

5. In a car-coupling, the combination, with 105 a draw-bar, a plate of inverted-U shape secured beneath the same and having a forwardly-projecting tongue at one side, a rod journaled horizontally through said plate and having a handle, and a dog fast on the rod between the sides of the plate, of a rotary jaw connected with said bar and resting normally 110 against the tongue, said jaw having a notch in normal alignment with the dog, and means for drawing the jaw away from said tongue.

6. In a car-coupling, the combination, with 115 a draw-bar, a vertical bolt passing therethrough, a bearing held by said bolt beneath the bar, a rod journaled in said bearing and having a handle, and a dog fast on said rod, of a rotary jaw connected with said bar forward of the bearing and having a notch in 120 normal alignment with the dog and means for turning the jaw.

7. In a car-coupling, the combination, with 125 a draw-bar and a stop beneath the same, of a rotary jaw mounted on said bar and having a beveled face, a weight bearing the jaw normally against said stop, and means for turning the jaw in the opposite direction.

8. In a car-coupling, the combination, with 130 a draw-bar having a stop, a rotary jaw on said bar having a beveled front face, and a weight holding the jaw normally against said stop, of

a slotted ear depending from the jaw and a rod passing through the slot, having a head beyond the same extending to the side of the car and having a handle.

5 9. In a car-coupling, the combination, with a draw-bar having a stop, a rotary jaw on said bar, and means for holding it normally against the stop, of a bracket on the car-body, having a slot, a rod connected with the jaw and passing through the slot, and a block depending from the rod, as and for the purpose set forth.

10 10. In a car-coupling, the combination, with a draw-bar having a stop, a rotary jaw on said bar, and means for holding it normally against

15 the stop, of a slotted ear depending from the jaw, a rod passing through said slot, having a head beyond the same and extending to the side of the car, a stop on said rod at the back of the ear, and an expansive spring between 20 the ear and stop.

25 11. In a car-coupling, the combination, with a draw-bar having a stop, a rotary jaw on said bar, and means for holding it normally against the stop, of a slotted ear depending from the jaw, a rod passing through said slot, having a head beyond the ear and extending to the side of the car, a stop on the rod at the back of the ear, an expansive spring between the ear and stop, and means for locking said rod 30 at the side of the car in one of two positions.

35 12. In a car-coupling, the combination, with a draw-bar having a stop, a rotary jaw on said bar, and a weight holding it normally against the stop, of a perforated ear depending from the jaw, a rod passing through the ear, having a head beyond it and extending to the side of the car, a stop on the rod at the back of the ear, an expansive spring between the stop and ear, a slotted bracket supported 40 by the car and through whose slot the rod

passes, and a block on the rod of a size to pass through the slot, as and for the purpose set forth.

13. In a car-coupling, the combination, with a draw-bar having a stop, a rotary jaw on said bar, and a weight holding it normally against the stop, of a slotted bracket on the car-body, a rod passing through the slot therein, a block depending from the rod and of a size to pass through said slot, and a yielding connection, 45 substantially as described, between the rod and the jaw permitting the latter to move from said stop, but limiting its movement in the other direction.

50 14. In a car-coupling, the combination, with a draw-bar having a stop, a rotary jaw mounted thereon and having a notch, and a weight holding the jaw normally against the stop, of a bearing beneath the bar, an oscillating rod journaled therein, a dog fast on the rod, and adapted to engage said notch, a second rod connected with said jaw, and a bracket on the car-body through which said rods extend.

55 15. In a car-coupling, the combination, with a draw-bar having a bearing, a rotary jaw mounted on the bar and having a notch, an oscillating rod turning in said bearing, and a dog fast thereon and adapted to engage said notch, of a second rod connected with said jaw and a bracket on the car-body through which 60 both rods extend.

70 In testimony that we claim the foregoing as our own we have hereto affixed our signatures in the presence of two witnesses.
